WASHING MACHINE

Reto Reikern, San Leandro, Calif.

Application July 1, 1936, Serial No. 88,420

15 Claims. (Cl. 8—159)

An object of my invention is to provide a washing machine which greatly simplifies the clothes washing process. Each phase of the cleansing process is improved and one of the advantages of the device lies in the fact that the clothes need not be handled between the washing and rinsing operations, and between the rinsing and drying operations. It also is possible to partially dry the clothes so that they remain damp enough for ready ironing, or to entirely dry the clothes by heat. The clothes may be entirely dried by heat, while still remaining in the washing machine.

It further is possible to heat the water in the washing machine to a boiling point and to continue to heat the water during the entire washing operation. The clothes container is rotatably mounted in the washing machine casing, and is rotated by jets of water and air playing against the cylindrical surface of the rotor or drum. In this way no actual gearing mechanism is needed between the source of power and the clothes-containing rotor. Moreover, the means used for rotating the rotor or drum is also used for cleaning the clothes.

One of the novel features of the invention lies in the manner of securing the clothes to the drum so that the clothes will be held against bunching. This will permit the washing fluid to more effectively permeate the clothes with a result that the clothes will be more effectively cleaned. The members which hold the clothes in the rotor or drum are preferably made hollow, and are perforated so that water and air can pass therethrough, and thoroughly wash the portions of the clothes actually contacting with the clothes-supporting members. The clothes-supporting members are also provided with helical grooves in their outer surfaces and the grooves in adjacent clothes-supporting members are spiraled in opposite directions so that water and air passageways will be formed at the juncture of the grooves in adjacent members. Certain of the clothes-supporting members are removable from the drum and these yieldingly contact with the fixed members for clamping the clothes in place. The removable members act in very much the same manner as clothes pins.

Other objects and advantages will appear in the following specification, and the novel features of the device will be particularly pointed out in the appended claims.

My invention is illustrated in the accompanying drawings forming a part of this application, in which—

Figure 1 is a vertical section through the device, portions being shown in elevation;

Figure 2 is a top plan view of a portion of the clothes container rotor or drum;

Figure 3 is a section along the line 3—3 of Figure 1, a portion of the casing being shown in elevation;

Figure 4 is a section along the line 4—4 of Figure 1; showing one of the clothes clamping members in elevation;

Figure 5 is an isometric view of one of the longitudinal clothes-supporting members;

Figure 6 is a side elevation of the device with the upper portion shown in section;

Figure 7 is an enlarged transverse sectional view through a portion of the drum, parts of the drum elements being shown in end elevation; and

Figure 8 is an isometric view of a member used in the device.

In carrying out my invention I provide a washing machine comprising a casing 1 mounted on a base 2. The upper portion 1—a of the casing cooperates with a bottom 3 for forming a water-holding chamber or compartment. The greater portion of the bottom 3 is cylindrical in shape, and the bottom is provided with a recess or pocket 4 in which I mount an electric heating element 5. A water discharge pipe 6 leads from the pocket 4 and a valve indicated generally at 7 controls the out-flow of water from the compartment. In Figure 3 I indicate an electric cord 8 removably connected to the heating element 5 in the usual manner.

The casing 1 is provided with a cover 9 that is hinged at 10. Figure 6 shows chains 11 or other suitable flexible means for holding the cover 9 in open position. The cover when in closed position forms a water seal for the top 1—a of the casing. The handle 12 shown in Figure 1 is provided for the cover.

In Figures 1 and 3 I show the two inner surfaces of the side walls of the casing provided with a U-shaped cradle indicated generally at 13. This cradle has vertical parallel tracks 13—a and a closed bottom 13—b that is non-circular. The two cradles 13 are designed to removably receive the square ends 14 of a shaft 15. The shaft, in turn, rotatably carries a clothes-containing drum or rotor, indicated generally at 16. It will be seen that the non-circular portions 13—b of the cradles 13 support the shaft 15 and prevent its rotation.

The drum or rotor 16 is provided with two end discs 17, and these discs are connected to each

other by a housing 18 that encircles the shaft 15. The housing 18 carries ball bearing races 19, and these ride on the shaft 15. I provide a packing indicated generally at 20 between each ball bearing race 15 and the disc 17. A lubricant is placed in the housing 18 and continuously lubricates the ball bearings 19. The packings 20 prevent this lubricant from escaping.

Near the rims of the discs 17 I provide longitudinally extending rods 21, see Figure 6. These rods are connected to the discs and aid in connecting the discs together. The periphery of the drum or rotor 16 is formed from a plurality of longitudinally extending members of different shapes. Certain of these members are permanently secured to the drum while others are removably disposed in place. In Figure 6 I show cylindrical members 22 extending between the discs 17 and held against removal by the rods 21. In Figure 7 I illustrate how the cylindrical members 22 are held against inward movement by beads 23 formed in the discs 17. The cylindrical members 22 are perforated throughout their lengths and are also corrugated. The corrugations extend in the form of a spiral from end to end of the cylinders.

I show the fixed cylinders 22 in groups of two, and between the cylinders in each group I provide a removable cylinder 24. Figure 7 shows this cylinder spaced from the cylinders 22, and further shows that this cylinder is perforated as at 25. The cylinder 24 also is provided with helical corrugations extending through the length thereof.

In Figure 4 I show how the cylinder 24 is removably held in place on the disc 17. The rim of the disc is rolled over to form a bead 26 and the cylinder 24 has an extension 27 that is formed into a clip for removably engaging with the bead 26. Both ends of the cylinder 24 are provided with the clips 27, and these clips engage with their respective beads 26. In addition to the clips 27 I provide clips 28, see Figure 4, that are struck up from the disc 17 and engage with the lower end portion of the cylinder. The perforations 25 are clearly shown in Figure 4 and so likewise are the spiral corrugations 29.

Between the removable cylinder 24 and the fixed cylinders 22 I provide secondary removable cylinders 30 which may be of the same diameter as the cylinders 22 and 24 but are preferably made of a smaller diameter. The cylinders 30 extend from end to end of the drum and are removably held in place by clips 31 engaging with the beads 26 in the same manner as the clips 27. The secondary cylinders 30 are split longitudinally along their under surface as at 32 and this gives the wall of the cylinder a spring action. When the cylinders 30 are placed in position between the cylinders 22 and 24 they will yieldingly contact with the walls of the latter cylinders. It will therefore be seen that they will grip any clothes that might be placed therebetween, and therefore the removable cylinders 30 may be likened to clothes pins. The bead 23 acts as a limit stop for the inward movement of the cylinders 30 as well as the cylinder 24.

I have described one group of longitudinal clothes-gripping members comprising the cylinders 22, 24 and 30. All of these cylinders are perforated and corrugated. The spiral corrugations in adjacent cylinders extend opposite to each other for the purpose already described. In order to give additional room for a greater number of clothes-supporting members, I form

certain of these members in the shape of triangles as shown at 33, in Figures 6 and 7. The members 33 extend along the length of the drum, and each encloses one of the rods 21. Figure 7 shows the triangular members split from end to end along one side as shown at 34. These members are perforated, and also are provided with corrugations. Figure 5 shows an isometric view of one of the members 33. In Figure 6 I show four of these triangular members 33 in a group and each is spaced from its adjacent member by a removable cylindrical member 30. The rib 23 and the rods 31 hold the triangular members 33 against inward movement. The entire circumference of the drum is formed from these three different types of members.

I will now describe how a sheet or other article of clothing may be secured in place in the drum. This is best illustrated in Figures 6 and 7. The end of the sheet 35 is shown depending from one of the fixed cylindrical members 22 and clamped against the member by two of the removable secondary members 30. The sheet is then looped at 36 between the fixed member 22 and removable member 24. The figure shows the secondary removable member 30 clamping the looped portion to the removable member 24. Figure 6 illustrates how a second looped portion 36-a is formed in the sheet 35. The member 30 disposed between the fixed member 22 and the removable member 24 has been removed, leaving a space for receiving the sheet. A positioning member shown in Figure 8 is used for forming the sheet into a loop. This member consists of a rectangular body 37 pivotally mounted on a cross portion of a U-shaped arm 38. The ends of the arm are bent outwardly as at 39, and are removably received in openings 40 in the sides of the casing 1. The member 37 has a handle 41 connected thereto.

The sheet 35 or other long piece of cloth extends from the removable member 24 in Figure 6 over the front edge of the casing 1. The pusher 37 is laid flat against the sheet, and then the sheet is brought over the upper surface of the pusher 45 and is looped back upon itself as shown at 36-b. The pusher 37 is now raised into the dotted line position, and its lower end is inserted in the space between the adjacent members 22 and 24. The pusher now is manually moved downwardly and will carry the looped portion 36-a of the sheet therewith. The pusher then is removed, and will leave the looped portion of the sheet in place. The removable member 30 is now placed in position, and will clamp the sheet to the two adjacent members 22 and 24. This process is repeated until the entire sheet has been looped into position and secured in place. Other garments of a smaller size may be looped over one or more of the members 22 or 33, and in this way will be held in place. Soiled portions of the garments may be disposed on the outer surface of the members 22 or 33 for a purpose hereinafter described.

I will now describe the novel means for rotating the drum and for washing the clothes. In Figure 1 I show a motor 42 or other suitable source of power. This motor drives a water pump 43 and an air pump 44. A pipe 45 leads from the bottom 3 to the water pump 43, and conveys water from the washing compartment to the pump. A pair of pipes 46 lead from the water pump upwardly along the corners of the casing 1 disposed adjacent to the front wall of the casing. The tops of the pipes 46 terminate adjacent

to the top of the casing. The cover 9 carries water pipes 47 that are formed with ends 48 designed to telescope slightly over the ends of the pipes 46, and thus form a water-tight seal. In the cover 9 I mount a header indicated generally at 49, and this header has a water-receiving compartment 50. The pipes 47 communicate with the ends of the compartment 50. Outlet jet openings 51 are formed in the under surface of the header 49 and communicate with the water compartment 50. The jets 51 are inclined at an angle for directing the water down upon upon the drum, and for rotating the drum in a clockwise direction when looking at Figure 1.

15 The air pump 44 delivers air to an air tank 52 by means of a pipe 53. Two air pipes 54 lead from the tank 52 and extend upwardly along the rear wall of the casing 1. The pipes preferably are disposed at the corners of the casing. The tops of the pipes 54 terminate at the top of the casing. Air pipes 55 are disposed in the cover 9 and are designed to telescope partially over the pipes 54 when the cover is closed. The telescoping of the pipes 55 over the pipes 54 will provide an air-tight seal. The header 49 has an air compartment 56 and the pipes 55 lead to the ends of this compartment. Air jets 57 are formed in the header 49 and communicate with the air compartment 56. These jets are inclined 20 for directing air down upon the drum for rotating the drum in a clockwise direction.

As a further means of rotating the drum I provide air pipes 58, see Figures 1, and 3, that lead from the air compartment 56 and terminate adjacent to the outer surfaces of the discs 17. Figures 1, 3, 4, and 7 show the discs provided with louvres 59 and these louvres extend in such a direction as to receive the air issuing from the pipes 58. The air when striking the louvres will 35 rotate the drum in a clockwise direction. It will be noted from Figure 7 that the louvres 59 are disposed adjacent to the interior of the members 22, 24, 30 and 33. The air therefore will enter the interior of these hollow members, and 40 will be forced through the perforations into contact with the clothes carried by the members, and thus aid in the cleaning operation.

As a further means of rotating the drum, and of forcing air through the clothes, I provide a 50 cross pipe 60, see Figure 1, that is connected to the two air pipes 54. The cross pipe 60 has a central pipe 61 depending therefrom, and this pipe leads to an air nozzle 62 that has a number of openings therein. During the operation of the 55 device air is forced through the air nozzle and strikes the drum in a direction to aid in its rotation. The air also will force its way through the perforated members and will agitate the clothes for washing purposes. The water line 60 in the casing 1 is substantially level with the axis of the shaft 15. The pipe 60 is disposed above the water line so that water cannot enter the air pipes 54. The discs 17 are provided with openings 63 for the passage of air and water. 65 The rear wall of the casing 1 has a door 64, see Figure 1, and this door has openings 65 therein to permit air to find its way to the air pump 44. A water inlet pipe 66 enters the casing 1 near the top of the rear wall and the open end of the 70 pipe directs the water down along the rear wall of the casing. Small water jets 67 are formed in the pipe so that a portion of the water in entering the casing will strike the drum. An exhaust air pipe 68 is disposed near the water inlet pipe 66. A flap valve 69 controls the flow of air

through this pipe for a purpose hereinafter described. Figure 6 shows the valve 69 mounted on a cross rod 70, and this rod has a handle 71 disposed on the outside of the casing 1. The handle is received in any one of a number of notches 72 so that the valve 69 may be in closed or partially opened position.

From the foregoing description of the various parts of the device, the operation thereof may be readily understood.

10 The various articles of clothing are secured to the members 22, 24, 30 and 33 in the manner already stated. Soiled portions of the clothing are preferably placed on these members so as to be exposed to the outside of the drum. The 15 triangular members are especially designed to support flat work.

The removable members may then be secured in place by a netting or cord shown at 73 in Figure 1. This netting is preferably as wide as 20 the length of the drum, and is passed beneath the drum and the free ends of the netting are supported by hooks 74 or other suitable fastening means. When the clothes are placed in the drum the ends of the netting are freed from the hooks and are tightly tied together to encircle the drum. A cord may be used in place of the netting if desired. The valve 1 of the drain pipe 6 is closed and the valve 75 of the water inlet pipe is opened. This will permit 30 water to enter the casing until it reaches the level shown at 76. This water preferably is near the boiling point, or if necessary it may be allowed to flow into the casing 1, and then heated by the element 5. The element 5 keeps the water to the boiling point or other desired temperature during the entire washing operation.

35 The cover 9 is now closed, and this will close a switch 77 connected in series with the motor circuit indicated generally at 78. A starting switch 40 79 may now be closed and the motor 42 will actuate both the water pump 43 and the air pump 44. The water pump 43 will draw water from the casing 1, and will force this water out through the jets 51 in the header 49 in the manner already described. The air pump 44 will force air through the pipes 54 and causes this air to issue from the jets 57 in the header 49, and to also issue from the nozzle 62 disposed at the end of the pipes 61. The valve 69 is opened to allow the 50 air to exhaust through the pipes 68.

The water and air jets issuing from the header 49 will strike the members forming the periphery of the drum, and not only will rotate the drum in the direction of the arrow, but also will 55 clean the portions of the garments enclosing certain of the longitudinal members. Air also will enter the interior of the longitudinal members by means of the pipe sections 58 and the louvres 59. This air will flow through the perforations in 60 the longitudinal members for a further cleaning of the clothes as well as impart rotation to the drum when striking the louvres.

The drum will rotate slowly and the clothes hanging from the top of the drum will just clear 65 the housing surrounding the shaft 15. These clothes will be carried down into the water, or other cleaning fluid, and will change from a depending position into a horizontal position. The water will be forced through the clothes that extend into the drum and a thorough washing of the clothes results. As the clothes are carried by the nozzle 62 they will be ballooned by coming into contact with the air issuing from the nozzle. This air will enter the drum through the perfo- 75

rations in the longitudinal members and will agitate the water in the drum as well as aid in rotating the drum. The air not only will agitate the water, but will cause the clothes to extend upwardly from the members as the members move past the position adjacent to the nozzle 62. The air in passing through the clothes will have a further cleaning effect.

The clothes then will be subsequently lifted clear of the water and the water will be allowed to partially drain therefrom before the clothes again are submerged in the water. This particular manipulation of the clothes prevents them from bunching and entirely cleanses all portions.

After the washing operation the water may be drained from the casing by opening the valve 7 and closing the valve 69. This will shut off the air from exhausting out of the casing with a result that an air pressure will be built up within the casing to aid in forcing the water therefrom. The drum will speed up in its rotation when the water is entirely drained from the casing and the device may be operated this way for a short time to permit a greater portion of the washing water to be removed from the clothes by centrifugal force. The valve 7 may now be closed and a rinsing water allowed to enter the casing by opening the valve 75. The clothes will be subjected to the rinsing water in the same manner as they were to the washing water. The rinsing water then may be drained off by building up an air pressure in the casing and opening the valve 7. A second rinsing water may be used if desired, or a bluing water may be added.

After the clothes are entirely cleaned the drum may be rotated to force all of the water from the clothes by centrifugal force. This may be continued until the clothes are dry enough for immediate ironing. It also is possible to entirely dry the clothes by merely allowing the heating element 5 to heat the air in the casing. This air will be drawn through the water pump in place of the water so that heated air will issue from the jets 51 in the header 49. The heater 5 will also warm the air in the space beneath the bottom 3 and this warm air will be drawn into the air pump 44 and will issue from the air jets 57 and 58. Heated air will also issue from the nozzle 62. This heated air will thoroughly dry the clothes.

The cover 9 now may be opened and the net or cord 73 removed from the drum. The clothes may now be removed from the machine by merely moving the removable members 24 and 30. It will be seen that the clothes are dried without the need of a wringer and that the clothes need not be handled between any one of the different operations already mentioned. The clothes are prevented from bunching while in the drum, and this results in a thorough cleaning of all portions of the clothes. Although the different longitudinal members are shown of various diameters, all of the members may be of the same diameter if desired. There are two methods of cleaning employed in the device, one is the use of jets of water and air playing against the clothes and the other is the actual moving of the clothes through a body of cleaning fluid. The device is especially designed to take care of all types of clothing from smaller articles to heavy blankets. The clothes are aerated during the washing operation which is a distinct advantage over the present methods.

While I have shown only the preferred form of my invention, it should be understood that various changes or modifications may be made with-

in the scope of the appended claims without departing from the spirit of the invention.

I claim:

1. In a washing machine, a drum having members extending parallel with its axis, certain of said members being removably secured to the drum, said removable members being disposed adjacent to the other members for gripping clothes between the members while allowing the clothes to extend into the drum, said members being perforated and provided with helical corrugations in their outer surfaces to permit water and air to pass therethrough during the washing operation.

2. In a washing machine, a rotatable clothes drum, discs forming the ends of the drum, hollow clothes-supporting members extending between the ends of the drum and having perforated walls, said members being spaced from each other, and a plurality of hollow clothes clamping members disposable between the first members for clamping the clothes in place, said last named members having perforated walls and each member being provided with a slot that extends throughout its length for giving a spring quality to the wall of the member, whereby the clothes clamping action between the fixed and removable members is enhanced.

3. In a washing machine, a casing for holding water, a clothes retaining drum rotatably mounted in the casing and having a perforated cylinder, means for clamping clothes to the cylinder, a cover for the casing, a header having a water-receiving compartment and an air-receiving compartment, said header having a plurality of jets leading from each compartment, and means for forcing water and air into their respective compartments in the header for causing the water and air to simultaneously issue from the jets and strike the drum for rotating it and for aerating and washing the clamped portions of the clothes, said means drawing its water supply from the water in the casing.

4. In combination, a casing for holding a cleansing fluid, a clothes-retaining drum rotatably mounted in the casing, a plurality of hollow perforated members constituting the periphery of the drum, said members being designed to clamp clothes in place in the drum, louvres formed in the ends of the drum and providing openings communicating with the interior of the hollow members, and means for directing air against the louvres for rotating the drum, this air passing into the hollow members and then through the perforations in the members for aerating the clothes carried by the members.

5. In combination, a casing for holding a cleansing fluid, a clothes-retaining drum rotatably mounted in the casing, clothes-holding members forming the cylindrical wall of the drum, means for removably securing certain of said members to the drum, said removable members being disposed between the fixed members and constituting clamps for holding the clothes against the fixed members, and a member retaining means designed to encircle the drum for holding the removable members against accidental detachment.

6. In a clothes cleansing machine, a clothes-holding drum comprising end discs each being provided with a beaded periphery, hollow members constituting the cylindrical wall of the drum, certain of said members being permanently secured to the discs, end clips carried by the re-

maining members and being removably secured to the beads for holding these members in place.

5 7. In a clothes cleansing machine, a clothes-holding drum comprising end discs each being provided with a beaded periphery, hollow members constituting the cylindrical wall of the drum, certain of said members being permanently secured to the discs, end clips carried by the remaining members and being removably secured 10 to the beads for holding these members in place, a number of the fixed members being cylindrical in shape while the others are triangular in cross section.

15 8. In a washing machine, a casing, a rotatable drum mounted therein, a plurality of clothes supporting members forming the periphery of the drum and being spaced from each other, and a clothes pusher pivoted to the casing and insertable between the members for causing the 20 portions of clothes disposed between the members to extend toward the axis of the drum.

25 9. In a washing machine, a casing, a rotatable drum mounted therein, a plurality of clothes supporting members forming the periphery of the drum and being spaced from each other, and a clothes pusher pivoted to the casing and insertable between the members for causing the portions of clothes disposed between the members, to extend toward the axis of the drum, and clothes 30 clamping means disposable between the members and cooperating therewith for securing the clothes to the periphery of the drum.

35 10. In a washing machine, means providing a drum in which the clothes are freely raised and dipped with respect to the liquid upon rotation of the drum, said means comprising spaced bars over which the clothes are looped to hang down inside, spaced heads to which the ends of the bars are connected to complete the drum, a shaft rotatably supporting the drum, and removable 40 bars placed between said first-named bars and bearing down on the clothes to keep them from slipping.

45 11. In a washing machine, a drum having hollow members extending parallel with its axis and contacting with each other to form the periphery of the drum, said hollow members being pro-

vided with spacing portions that will aid in gripping the clothes and in permitting water to pass between the members.

12. In a washing machine, a casing for holding water, a clothes retaining drum rotatably mounted in the casing, a header placed adjacent to the drum periphery and having a water-receiving compartment and an air-receiving compartment, said header having a plurality of jets leading from each compartment, and means for forcing 10 water and air into their respective compartments in the header for causing the water and air to issue from the jets and strike the drum for rotating it and for cleansing the clothes by penetrating the mesh of the fabric, said means drawing 15 its water supply from the water in the casing.

13. The herein described method of washing clothes which consists in rotating the clothes through a fluid so that during a part of the rotation the clothes are passing through the fluid 20 while the remainder of the cycle the clothes are lifted above the fluid, ballooning the clothes with air during a portion of their passage through the fluid, and directing a fluid spray against the clothes during a portion of their pas- 25 sage through the air.

14. The herein described method of washing clothes which consists in gripping the clothes and rotating them through a fluid without causing them to tangle, lifting the clothes clear of 30 the fluid during a portion of the rotation, and in directing a spray of fluid against the gripped portion of the clothes during the time they are clear of the fluid for causing the spray to penetrate the mesh of the clothes.

35 15. The herein described method of washing clothes which consists in gripping the clothes and rotating them through a fluid without causing them to tangle, lifting the clothes clear of the fluid during a portion of the rotation, and in directing a spray of fluid against the gripped portion of the clothes during the time they are clear of the fluid for causing the spray to penetrate the mesh of the clothes and in ballooning the clothes with air during a portion of their 40 movement through the fluid.

RETLO ROLKERN.
